UNITED STATES PATENT OFFICE.

HUGO H. WERMINE, OF VILLA PARK, ILLINOIS, ASSIGNOR TO BELDEN MANUFACTURING COMPANY, OF CHICAGO, ILLINOIS, A CORPORATION OF ILLINOIS.

WIRING PANEL FOR ELECTRICAL APPARATUS.

Application filed September 9, 1927. Serial No. 218,384.

This invention relates to wiring panels for electrical apparatus and has particular reference to means for wiring a radio set, although adaptable for use in connection 5 with other forms of electrical apparatus.

One object of the invention is to provide means whereby such electrical apparatus as above mentioned may be easily and quickly wired by an unskilled person, and without 10 the use of numerous or expensive tools. Another object is to provide such wiring means which will practically insure proper connection of the various elements constituting the apparatus.

15 A further object of the invention is to provide wiring means of the class described which can be economically manufactured in a shop and sold as a unit to the builders of the apparatus for which the unit is intended.

20 Still further objects of the invention are to provide a wiring panel construction which is adaptable to practically any desired form of electrical circuit, such as, for instance, any of the present day radio circuits; to provide 25 a wiring panel which will be effective, as an incident to its wiring function, to support the devices which it connects; and to provide a structure of the class described which will be neat and compact and will enhance 30 the appearance of a connected group of electrical devices by eliminating the usually numerous exposed wires extending in various directions and also by grouping such devices according to a predetermined plan.

35 It is also an object of the invention to provide an improved method of making the wiring panel and in general to provide an improved device of the class described.

40 Other objects and advantages of the invention will be understood by reference to the following specification and the accompanying drawings in which I have illustrated one form of the invention embodied in a radio 45 receiving set, and in which drawings—

Figs. 1, 2 and 3 are plans, respectively, of three layers of panel and wiring which are adapted to be assembled, by being superposed, to form a unitary wiring panel.

50 Fig. 4 is a plan illustrating the unitary panel consisting of the above mentioned three layers when assembled.

Figs. 5 and 6 are cross sections of a radio receiving set illustrating the method of 55 using the panel to connect a plurality of

radio electrical devices into a radio receiving circuit, these figures including sections of the panel taken on the lines 5—5 and 6—6, respectively, of Fig. 4.

Referring to the drawings, I have indicated in Fig. 1 a panel-layer or sheet 10, preferably of a phenol condensation insulating material such as "bakelite" or other suitable insulating material. The material used is preferably such that it may be 60 formed into pliable and semi-cured sheets which may subsequently be completely cured and hardened. The pliable or semi-cured sheet 10 is provided with one or more apertures or notches 11 for a purpose which will 65 presently appear. One or more conductor members 12 are disposed on the face of the layer 10 and arranged thereon according to a predetermined plan. The conductors are 70 preferably formed of relatively thin flat 75 strips of electrical conducting metal such as copper or brass, and are provided with terminal portions where desired, such as indicated at 13 and 14. The terminal portions 13 project into the apertures 11, and the terminal portions 14 project outwardly from the panel, preferably projecting from an 80 edge thereof.

In Fig. 2, I have illustrated a panel or sheet 15 similar in size and form to the 85 sheet 10. The sheet 15 is also preferably apertured as at 16 in accordance with the arrangement of the apertures or notches 11 in the sheet 10. One or more conductor members 17, similar in construction to the conductors 12, are disposed in the desired arrangement on the sheet 15 and are provided with terminal portions 18 projecting into the various apertures and terminal portions 19 projecting outwardly from the edge of 90 the sheet.

In Fig. 3, I have illustrated a third panel-layer or sheet 20 similar to the sheets 10 and 15 and similarly notched or apertured, as indicated at 21. A plurality of conductors 100 22 are arranged on the face of the sheet 20 and are provided with terminal portions 23 extending into the apertures 21 and terminal portions 24 extending outwardly from the edge of the sheet.

The wiring panel, according to the present invention, is formed by superposing the sheet 15 and conductor members disposed thereon over the sheet 10 and its conductors, and then superposing the sheet 20 with its conductors 110

over the sheet 15. It will be apparent that the construction so far described consists of three separate, superposed layers of pliable or semi-cured insulating material, between the 5 adjacent faces of which there are arranged sets of conductors disposed according to a predetermined plan. A fourth layer or sheet of insulating material 53 (Fig. 5) having apertures and notches similar to those in the other 10 layers is superposed over the third sheet so as to cover the conductors thereon, and the four superposed sheets are then pressed together so as to firmly grip the conductors therebetween and to embed the same in the adjacent 15 sheets, after which the superposed sheets are completely cured so as to form a one-piece panel having a plurality of conductors embedded therein. This one-piece panel structure with conductors embedded therein is illustrated in section in Figs. 5 and 6, the planes 20 in which the various sheets or layers are united being indicated by light lines 54 extending across the width of the panel. As shown in Fig. 4, the pressed and cured panel 25 structure results in a wiring unit having the desired terminals projecting outwardly from the edge thereof for receiving connections from batteries or other sources of electrical energy or other electrical devices. The panel 30 thus formed also is provided with a plurality of apertures indicated at 24 into which the terminal portions of the various sets or layers of conductors project for facilitating connection thereto of the desired electrical or radio 35 devices.

The construction described has been found to be very desirable for various reasons, including the fact that it is possible to arrange the various conductors relative to each other 40 so that there will be a minimum coupling or induced electrical effect from one of the conductors to another. This feature is obviously of great importance in connection with radio apparatus.

45 The arrangement of conductors and terminals disclosed in the present embodiment of the invention is for the radio circuit commercially known as the Pfanzstiehl circuit. The notch 25 indicated at the upper left hand 50 corner of the panel is provided for the purpose of permitting connection and mounting of a suitable switch member 26, as shown in Fig. 5. As shown in this figure, the wiring panel designated 27 is fixedly mounted relative to a suitable front panel 28 by means of a 55 plurality of mounting brackets 29. The switch 26 is of a type which is secured to the front panel 28 and is controlled by means of a knob 30. The terminals 31 and 32 of the 60 switch member 26 are connected respectively to the source of electrical energy and to the terminal 14 which is a part of the conductor 12 of the first set or layer of conductors. Radio frequency coils, such as indicated at 65 33 in Fig. 5, are connected by means of conduct-

tors 34, 34 to the proper terminals projecting into the apertures 35 of the panel 27.

Suitable variable condensers, one of which is indicated at 36 in Fig. 5, may be mounted on the panel 27 by means of screws 37 or other suitable means, apertures 38 being provided in the panel for permitting the passage of the screw 37 therethrough, without contacting with any of the various conductors embedded in the panel. Apertures 39 are also provided 75 in the panel 27 for permitting the passage therethrough of the condenser operating shaft, one of which is indicated at 40 and which is connected to a dial 41 disposed in front of the panel 28. 80

Radio tube holders or sockets such as indicated at 42 may be connected, as clearly shown in Fig. 6, to the proper terminals projecting into the apertures 43 in the panel, and audio transformers such as indicated at 44 85 may be connected to the proper terminals projecting into the apertures 45. Apertures indicated at 46 and 47 serve to expose terminal portions for receiving condensers required by the radio circuit for which the present panel 90 is arranged, and the notch indicated at 48 is provided for facilitating mounting of a jack 49 which is connected to terminals projecting into the said notch from the edge of the panel. 95

The construction of the panel is such that 100 the terminal portions which project into the apertures and receive terminal portions of the various devices will be sufficiently rigid to support the devices connected thereto in substantially fixed position relative to each other. If desired, suitable fixed resistances indicated at 50, 51 and 52 may be embedded in the panel between two of the layers and connecting certain of the conductors as required by the circuit for which the panel is designed. 105

For other circuits requiring a lesser or greater number of conductors and terminals it may be desirable to vary the arrangement of the conductors as well as the number of 110 layers of panel material and number of layers or sets of conductors. For a simple circuit involving relatively few conductors, it may be found practical to include all of the conductors between two sheets of insulating material, provision being made for insulating 115 conductors which of necessity must cross one another. Such a provision might include, for example, a relatively thin flat piece of insulating material positioned between the overlapping or crossing parts of the conductors. For more complicated circuits requiring a greater number of conductors, it is preferable to separate the conductors so that where one crosses another it is separated therefrom by a layer or sheet of the insulating panel material, and it is obvious that as many layers as required may be combined to form a unitary wiring panel of the class described. 120 125

The described details of the invention being illustrative of only a single embodiment 130

thereof, the scope of the same should be determined by reference to the following claims, which should be construed as broadly as possible consistent with the state of the art.

5. I claim as my invention:

1. Means for wiring an electrically operated apparatus comprising a panel of insulating material provided with an opening extending therethrough, said opening being disposed adjacent an electrical device constituting part of the apparatus, a plurality of conductors embedded in said panel, some of said conductors having terminal portions integral therewith and projecting outwardly from the

15 panel for facilitating connection of such conductors in the desired electrical circuits, and some of said conductors having terminal portions integral therewith and projecting into said opening for receiving the terminals of 20 said adjacent electrical device, thereby to connect said device into the circuit of such conductors.

2. Means for wiring an electrically operated apparatus, comprising a panel of insulating material, a plurality of independent conductors embedded in said panel, some of said conductors having terminal portions integral therewith, accessible from the exterior of said panel and adapted to be electrically connected to adjacent parts of said apparatus, and some of said conductors having terminal portions integral therewith and projecting outwardly from said panel for facilitating connection of such conductors in the desired 25 electric circuits.

3. In a radio set, the combination of a plurality of electrical devices, means for connecting said devices in a predetermined radio circuit including a plurality of conductors having terminal portions for receiving certain terminals of certain of said devices, and means for maintaining said conductors in relatively fixed position and relatively insulated, thereby causing said terminal portions 30 to be effective to support the respective devices in said predetermined position.

4. In a radio set, the combination of a plurality of electrical devices, means for electrically connecting said devices in a predetermined radio circuit, said means including a plurality of conductors having terminal portions for receiving terminals of certain of said devices, said conductors being spaced apart so as to prevent electrical contact therebetween, and a panel of insulating material encasing said conductors and provided with openings for exposing said terminal portions, said panel being effective to maintain said conductors in said relatively spaced position, and also to cause said terminals to be effective to support the respective devices connected thereto.

5. In a radio set, the combination of a plurality of radio devices, means for connecting said devices in a predetermined radio circuit

and comprising a panel of insulating material, a plurality of laterally spaced and relatively insulated sets of conductors embedded in said panel, each of said sets including a plurality of relatively insulated conductors 70 disposed in a plane common to all in the set, portions of some of the conductors in one set overlapping portions of the conductors in the other set, some of said conductors having terminal portions arranged in groups for facilitating connection of certain of said radio devices thereto, and said panel being provided with openings for exposing said groups of terminals.

6. In a wiring panel for electrical apparatus, the combination of a layer of insulating material, a set of conductors on one face of said layer, a second layer of insulating material on said face and disposed over said set of conductors, a second set of conductors disposed on the outer face of said second layer of insulating material, some of the conductors of said second set overlapping some of the conductors of said first set, and another layer of insulating material disposed over 90 said second set of conductors, said layers of insulating material being united to form a unitary panel structure having a pair of relatively insulated sets of conductors enclosed therein, and some of said conductors having 95 portions accessible from the exterior of the unitary panel structure for facilitating connection of such conductors in the desired electrical circuit.

7. In a wiring panel for electrical apparatus, the combination of a layer of insulating material, a plurality of separate conductors arranged in a common plane on one face of said layer, a second layer of insulating material on said face and disposed over said set 105 of conductors, a second set of similarly arranged independent conductors disposed on the outer face of said second layer of insulating material, some of the conductors of said second set overlapping some of the conductors 110 of said first set, and another layer of insulating material disposed over said second set of conductors, said layers of insulating material being integrally united to form a unitary panel structure having a pair of relatively 115 insulated sets of conductors enclosed therein, the conductors in each set being maintained in a relatively fixed position, and some of said conductors having terminal portions projecting from the unitary panel structure for 120 facilitating connection of such conductors in the desired electrical circuit.

8. In a wiring panel for electrical apparatus, the combination of a layer of insulating material, a set of conductors on one face of 125 said layer, a second layer of insulating material disposed over said set of conductors, a second set of conductors disposed on the outer face of said second layer of insulating material, some of the conductors of said 130

second set overlapping some of the conductors of said first set, and another layer of insulating material disposed over said second set of conductors, said layers of insulating material being united to form a unitary panel structure having a pair of relatively insulated sets of conductors enclosed therein, said unitary panel structure being provided with cut-out portions for exposing terminal portions of some of said conductors for facilitating connection of such conductors in the desired electrical circuit.

9. In a wiring panel for electrical apparatus, the combination of a layer of insulating material, a set of conductors on one face of said layer, a second layer of insulating material disposed over said set of conductors, a second set of conductors disposed on the outer face of said second layer of insulating material, some of the conductors of said second set overlapping some of the conductors of said first set, and another layer of insulating material disposed over said second set of conductors, said layers of insulating material being united to form a unitary panel structure having a pair of relatively insulated sets of conductors enclosed therein, said unitary panel structure being provided with a cut-out portion for exposing terminal portions of some of said conductors for facilitating connection thereof in the desired electrical circuit, and some of said conductors having portions extending outwardly from an edge of the panel structure also for facilitating connection of such conductors in the desired electrical circuit.

10. Means constituting a wiring unit for connecting a plurality of electric devices in a predetermined circuit, comprising a panel of insulating material, a plurality of relatively insulated conductors enclosed in said

panel, some of the conductors having portions disposed in overlapping relation to portions of some of the other conductors, the overlapping portions being spaced from each other so as to maintain said conductors insulated from each other, and some of said conductors having terminal portions accessible from the exterior of said panel for facilitating connection of such conductors in the desired circuits.

11. Means constituting a wiring unit for connecting a plurality of electric devices in a predetermined circuit, comprising a panel of insulating material, a plurality of laterally spaced sets of conductors enclosing said panel, the conductors of each set being relatively insulated, and said sets being insulated from each other, some of the conductors of one set having portions overlapping portions of some of the conductors of the other set, and some of the conductors having portions accessible from the exterior of said panel for facilitating connection of such conductors in the desired circuit.

12. Means constituting a wiring unit for connecting a plurality of electric devices in a predetermined circuit, comprising a panel of insulating material, a plurality of laterally spaced sets of conductors enclosing said panel, the conductors of each set being relatively insulated, and said sets being insulated from each other, some of the conductors of one set having portions overlapping portions of some of the conductors of the other set, and some of the conductors having portions accessible from the exterior of said panel, said panel being effective to maintain said accessible portions in relatively fixed position whereby said portions are adapted to serve as supports for the devices connected thereto.

HUGO H. WERMINE.
